(57) **CLAIM**

The ornamental design for a trigger housing for a firearm, as shown and described.

DESCRIPTION

FIG. 1 is a perspective view of a trigger housing for a firearm with trigger assembly environment;

FIG. 2 is a perspective view thereof;

FIG. 3 is a top view thereof;

FIG. 4 is a bottom view thereof;

FIG. 5 is a rear view thereof;

FIG. 6 is a front view thereof;

FIG. 7 is a side view thereof; and,

FIG. 8 is a side view thereof.

The broken lines are for purposes of illustrations only and form no part of the claimed design.

The broken lines in the drawings depict portions of the trigger housing for a firearm that form no part of the claimed design.

1 Claim, 5 Drawing Sheets
